CAN HEAD AND METHOD OF HERMETICALLY SEALING FILLED CANS

William H. Brooks, Oconomowoc, Wis., assignor to Carnation Company, Oconomowoc, Wis., a corporation of Delaware

Application September 22, 1932, Serial No. 634,324

3 Claims. (Cl. 220—44)

This invention relates to can heads and a method of hermetically sealing filled cans.

Heretofore, in the automatic machine filling and sealing of cans such as are used as containers for food products of various kinds, it has been the practice to provide one of the can ends or heads with a filling or vent hole which, after the can has been filled and said head applied and secured to the can body, is then sealed by first applying a fluxing agent around the edges of the hole for uniting a solder to the metallic head of the can, whereby said vent hole is hermetically sealed. In this automatic tipping or sealing operation, it not infrequently happens that imperfect sealing results from the inability of the flux to de-oxidize the surface of the can at the edge of the filling or vent hole by reason of the presence of foreign matter, such as the overflow of the contents of the can, excessive oxidation of the oil coating on cans usually made from tin plate, or from rust occasioned by long exposure of the metal of the can to moisture laden air. In such cases, the proper sealing of the cans is rendered very difficult.

It is the primary object and purpose of my present invention to eliminate the above difficulties, and secure a more positive and reliable tipping or sealing of the vent holes of the cans while enabling such operation to be very rapidly executed by the automatic tipping machines. To this end, my new method consists in applying a fluxing substance prior to filling the can to the surface of the part to which the sealing solder is to be applied, in order thereby to prevent contamination of such surface by the contents of the can. The fluxing substance is preferably of a protective nature, not greatly altered by age or contact with the metal of the can, and preferably applied during or immediately after fabrication of the can.

An additional object of the invention is to avoid the contamination of food, medical and pure chemical substances usually packed in sealed containers, by applying to the clean surface of the container head directly after manufacture, a mild fluxing substance, in the absence of which, after such surface has been soiled by age or overflow of the contents, a much more corrosive and powerful fluxing agent is required, small quantities of which will seriously contaminate the contents of the can.

My invention also has for a further object to provide as a new article of manufacture, such a can head or end having a filling and/or vent hole therein and the fluxing material applied

around the edges thereof and preventing oxidation of the metal. In one embodiment of the invention, this fluxing material is applied in the form of a film which also extends across and closes the vent hole to prevent the entrance of dust or dirt to the interior of the can while the empty cans are held in storage.

With the above and other objects in view, the invention consists in the improved can head, and in the new method of hermetically sealing filled cans, as will be hereinafter more fully described, illustrated in the accompanying drawing and subsequently incorporated in the subjoined claims.

In the drawing wherein I have shown a preferred embodiment of my improved can head, and in which similar reference characters designate corresponding parts throughout the several views,—

Figure 1 is a plan view of the can head showing the solder fluxing material as applied there- 75 to in the manufacture of the cans;

Fig. 2 is a sectional view taken on the line 2—2 of Fig. 1 showing the filling hole of the can head sealed by the solder;

Fig. 3 is a view similar to Fig. 1 showing a 80 further embodiment of the invention in which the flux material extends in a film over the vent hole of the can head, and

Fig. 4 is a sectional view taken on the line 4—4 of Fig. 3. 85

In carrying out my present invention, the cans in accordance with one well known process of manufacture, consist of the usual cylindrical body of tin and ends or heads having marginal rims which are soldered to the ends of the can body. One of these heads, herein indicated generally at 5, is centrally provided with the filling hole 6 adapted to be hermetically sealed after the can has been filled so as to preserve and protect the contents thereof and enable the same to be maintained in edible condition for a prolonged period of time. This sealing of the filling or vent holes is accomplished by automatic tipping or sealing machines of a type well known in the art, in which a fluxing agent or material is first applied to the metal can head around the hole and the solder then applied and thus permanently united to the metal can head. My present invention differs from this usual practice, in that the can head 5 in the manufacture thereof is provided with the plasticized fluxing material indicated at 7 around the edges of the hole 6. If desired, this fluxing material may be deposited or applied in the form of a film indicated at 7 in Figs. 3 and 4 of the drawing which extends over 110

and completely closes the hole, thereby excluding dust or dirt from the interior of the can while the cans are in storage. In filling the can, the central portion of the film 7 is, of course, first 5 removed. In both cases, this fluxing material also serves to prevent oxidation of the metal can head around the edges of the hole, such oxidation having been found under the present practice to seriously impair the proper application 10 of the fluxing material and thereby render the final sealing of the hole in the automatic tipping machines more or less difficult.

By the provision of the pre-fluxed can head, after the can has been filled with the commodity, 15 a very positive and reliable soldering and sealing of the filling or vent hole is obtained in the automatic tipping machine.

From the above description considered in connection with the accompanying drawing, the nature 20 of my present invention and its several advantages in practical use will be clearly and fully understood. By means thereof, it will be evident that the operation of hermetically sealing the filling or vent holes of cans such as are used in 25 vending various food commodities may be very rapidly and accurately executed, insuring the complete protection of the contents of the cans, and appreciably reducing operation cost in connection with this step in the packaging and 30 vending of food stuffs. While the invention as

herein disclosed is of very simple character, it is nevertheless possible that variations in such disclosures may be resorted to while substantially procuring all the advantageous results. Accordingly, it is to be understood that in practice, I reserve the privilege of resorting to all such legitimate changes as may be fairly embodied within the spirit and scope of the appended claims.

I claim:

1. A method of filling and sealing cans which consists in first providing one head of the can with a hole, then applying a soldering flux to the can head around the edge of said hole, then filling the can, and finally applying the solder to the previously fluxed can head to seal the hole. 85

2. As a new article of manufacture, a one piece can head having a hole thereon, and a solder fluxing material on the can head extending in a film over said hole and closing the same. 90

3. As a new article of manufacture, a can adapted to be filled and having a filling opening in the head wall thereof, and a coating of solder fluxing material on the external surface of the can at the edge of said opening and adapted to protect the edge of the opening from contamination and adapted to coact with the subsequently applied sealing means for said opening to permanently unite the same with the can wall after the can has been filled. 95
